ILLUMINABLE GAME APPARATUS

Julius F. Hullman, Cleveland, Ohio

Application March 26, 1958, Serial No. 50,188

Term of patent 7 years

(Cl. D34—5)

The single figure is an isometric view of an illuminable game apparatus, showing my new design.

The undisclosed side and rear of the illuminable game apparatus are substantially plain in appearance.

I claim:

The ornamental design for an illuminable game apparatus, substantially as shown and described.
